Primary Examiner—Janice Seeger
Assistant Examiner—Zenia I. Bennett(57) **CLAIM**

The ornamental design for a toy, as shown and described.

DESCRIPTION

FIG. 1 is a front perspective view of the present toy, wherein the portion of the toy shown in phantom is not part of the design sought to be patented and is provided for environmental purposes only.

FIG. 2 is a front elevation view of FIG. 1, wherein the portion of the toy shown in phantom is not part of the design sought to be patented and is provided for environmental purposes only.

FIG. 3 is a rear elevation view of FIG. 1.

FIG. 4 is a left side view of the present toy, and the right side view is a mirror image thereof, wherein the portion of the toy shown in phantom is not part of the design sought to be patented and is provided for environmental purposes only.

FIG. 5 is a top view of FIG. 1; and,

FIG. 6 is a bottom view of FIG. 1.
